HAND-OPENABLE TOP FOR CANS

Louis Fried, Philadelphia, Pa.

Application October 31, 1952, Serial No. 318,130

10 Claims. (Cl. 220—48)

The present invention relates to improvements in can tops adapted to be applied by conventional canning machinery and more particularly relates to an improved can top which is hand-openable and does not require the use of can openers of the various well-known types.

In cans of the prior art, it is usually necessary that a separate can opener be utilized for opening the can top. An objection to the use of separate can openers is that one must be available when it is desired to open a can. Furthermore, when using separate can openers, they must be either made so durable as to be able to open a large number of cans and, therefore, be expensive or they may be constructed inexpensively requiring frequent replacement. Can openers have heretofore been incorporated on cans, such as for example, the key-type of opener, but this type is notoriously difficult to manipulate and there is always the chance that the key will become lost prior to use.

Reference is made to my copending application, Serial No. 318,129 filed October 31, 1952, for a disclosure of one form of can top which obviates the difficulties encountered in prior art arrangements. In the form shown in that application, the opening in the can top is effected by first removing a center portion of the plate of the can top, the subsequent forming of the removed center portion into a cutting instrument, and finally, the cutting of the sealing plastic sheet by that cutting instrument.

It is, therefore, a primary object of the present invention to provide an improved can top which will overcome the difficulties encountered in prior can tops and yet which will provide an effective sealing closure for cans.

Another object of the present invention is to provide an improved can top which will require the use of no can openers or other separate can opening device such as a key or the like and yet which will be of extreme simplicity and not require a complex procedure for effecting the opening.

Still another object of the present invention is to provide an improved can top arrangement wherein by the simple expedient of pivoting a portion of the can top relative to the remainder thereof, an opening is formed in the frangible sealing means which constitutes part of the cover, thereby obviating the requirement for forming a cutting instrument to fracture the sealing means.

A further object of the present invention is to provide an improved can top which has incorporated therein means for simply effecting an opening for access to the can contents and wherein the cost of the can top is not materially greater than that of conventional can tops.

Various other objects and advantages will become apparent from the detailed description to follow.

A preferred form in which I have contemplated applying my invention is clearly illustrated in the accompanying drawings wherein:

Fig. 1 is a perspective view of a can to which one of my improved can tops has been applied;

2

Fig. 2 is a perspective exploded view of the several component elements of my improved can top;

Fig. 3 is a vertical sectional view taken substantially along the plane of line 3—3 of Fig. 1 and showing the dotted line position of the component elements prior to and subsequent to effecting the opening in the top; and

Fig. 4 is a perspective view showing the cutting of the plastic sheet by the portion of the plate that has been pivoted about its joiners.

Referring now more particularly to the drawings wherein like numerals designate like parts throughout, and having reference to Figs. 1 and 2 of the drawings, it will be seen that my improved can top, designated generally by the numeral 10, for the can C, is comprised of the substantially flat and circular plate 12, frangible plastic disc 14, operating strap 16 and protective clip 18. Although the showing is of a conventional metallic cylindrical can, it will be understood that various other shapes of and material for cans are contemplated.

The substantially flat and circular plate 12 is essentially of conventional can top construction in that it is comprised of the usual depressed portion 20, the relatively raised annular portion 22 adjacent thereto, the annular arcuated rib portion 24, the annular flat portion 26, which is substantially coplanar with the annular portion 22, and finally the peripheral flange portion 28. As will be understood, the flange portion 28 cooperates with the flange 30 at the upper end of the conventional can C to form the usual sealing seam at 32, as shown best in Fig. 3. The seam shown is formed by the conventional canning machinery and my improved can top can be fed by the usual equipment without requiring any changes.

The center depressed portion 20 and the surrounding flat portion 22 are formed with slit formations at 34 and 36. Slit 34 includes slit portion 38 in spaced parallel relation to a diameter 39 of the can top and the two leg portions 40 and 42 of the slit which extend along divergent paths from the ends of the slit portion 38 to approximately the diameter 39. Slit 36 is comprised of the two slit portions 44 and 46 which diverge from a point 48 on the annular portion 22 of the cover to approximately the diameter 39. The ends of the slits 40 and 42 terminate in juxtaposition to the ends of the slits 44 and 46, respectively, at the diameter 39, so as to provide narrow joiners at 50 and 52 which connect the substantially triangular can top portion 54, which is otherwise substantially separate, with the encircling or surrounding can top portion.

The can top plate 12 is provided with a slot at 56 in the annular flat portion 26 radially outwardly of the point or vertex 48 of the triangular portion 54. The substantially triangular portion 54 is provided with an offset portion at 58, see Figs. 3 and 4, at the ends of which aligned slots 60 and 62 are provided, the axis of the slots being perpendicular to the diameter 39 and substantially in line with the vertex 48. The portion 54 is also provided with a struck-out portion 64 which forms a tongue 66 for a purpose to be described hereinafter.

The frangible plastic disc 14 is formed of thin sheet polyethylene because of its desirable properties. However, any other material which will effect a seal between the plate flange 28 and can top flange 30 at the seam 32 and which will also protect the food in the can C over the requisite range of temperatures may be employed. The diameter of the disc 14 shown is greater than that of the plate 12 for the reason that the disc is conformed to the contour of the underside of the plate, including its peripheral flange, prior to placing the can top in the feeding mechanism.

The strap 16 is formed of an elongated strip of relatively stiff metallic stock or other suitable material, the width thereof being approximately equal to the width of the

slots 60 and 62. The strap has one end portion offset at 68 so as to provide a finger engaging portion.

The protective clip 18 is substantially of U-shaped form and includes a short leg 70 and a long leg 72 joined by a bight portion 74 so that the legs are in close parallel relationship.

In assembly, the strap 16 is passed through the slots 60 and 62 beneath the offset 58 of the triangular portion and has the end 76 engaged beneath and against the tongue 66, the finger-engaging portion 68 lying over the rib 24. The protective clip 18 is of bendable material so that the short leg 70 can be disposed through the slot 56 and beneath the plate 12 with its free end 71, underlying the point or apex 48 as seen best in Figure 3. The long leg is adapted to overlie the triangular portion 54 so that the two legs releasably retain the triangular portion from accidental displacement. The plastic disc 14 is disposed on the undersurface of the can top and secured thereto, especially at the flange 28.

The can top can then be applied to a can filled with food or beverage in the conventional fashion.

When it is desired to remove the contents of the can, the user merely bends the long leg 72 of the protective clip 18 to the dotted line position 72' of Fig. 3 and then completely removes the clip. Next the strap 16 is moved upwardly, by engaging the portion 68, to the dotted line position 16'. The strap 16 and the substantially triangular portion 54 move together and pivot about an axis substantially coincident with the diameter 39, the joinders 50 and 52 twisting during the operation. The apex 48 of the triangular portion is thereby depressed, puncturing the plastic sheet and the continued pivoting action severs the plastic sheet along the lines 78 and 80 as seen in Fig. 4. In this fashion a triangular opening in the can top is effected out through which the beverage can be dispensed. If desired, the triangular portion 54 and strap 16 can be completely removed by rocking the same back and forth until fracture occurs at the joinders 50 and 52.

It will be realized that various mechanical modifications and substitutions can be made which fall within the scope of my invention as set forth in the appended claims.

It will thus be seen that I have provided a can opening arrangement wherein it is unnecessary to effect any cutting of the metal of the can in view of the pre-cutting or pre-slitting as above described. Therefore, the possibility of slivers of metal, often occurring as a result of the operation of conventional can-openers, falling into the food to become involved in human consumption, is entirely obviated.

What is claimed is:

1. A hand-openable can top comprising a substantially flat plate of a shape similar to that of a can to which it is to be applied, a pair of slits in said plate with both ends of one slit terminating adjacent the respective ends of the other slit providing narrow joinders between the slits lying in a diametrical line of the plate, the major portion of each slit being spaced from the corresponding portion of the other slit so as to define a can top portion substantially separate from an encircling portion and extending across said diametrical line and the major part of the top portion between the slits, and means carried by said can top portion for effecting displacement of said can top portion and for effecting rotation of the same relative to the encircling portion on said diametrical line so as to provide an opening in said can top for access to the contents of the can.

2. A hand-openable can top comprising a substantially flat plate of a shape similar to that of a can to which it is to be applied, a pair of slits in said plate with both ends of one slit terminating adjacent the respective ends of the other slit providing narrow joinders between the slits lying in a diametrical line of the plate, the major portion of each slit being spaced from the corresponding portion of the other slit so as to define a can top portion attached only by said joinders to an encircling

portion, frangible sealing means on the underside of said plate for effecting a sealing closure for the top opening of the can when said can top is engaged thereon, and means carried by said can top portion for effecting displacement and rotation of said can top portion on said diametrical line relative to the encircling portion so as to fracture the frangible sealing means and provide an opening in said can top for access to the contents of the can.

10 3. A hand-openable can top according to claim 2 wherein said frangible sealing means is comprised of a sheet of plastic material adapted to sealingly bond that periphery of the can top to the open top of the can.

4. A hand-openable can top comprising a substantially flat plate of a shape similar to that of a can to which it is to be applied, a pair of slits in said plate with the ends of one slit terminating adjacent the respective ends of the other slit, the major portion of each slit being spaced from the corresponding portion of the other slit so as to

20 define a can top portion substantially separate from an encircling portion, and means for effecting displacement of said can top portion relative to the encircling portion so as to provide an opening in said can top for access to the contents of the can, said means including an

25 elongated, relatively stiff, substantially flat strap, said can top portion having means for holding said strap thereto for movement together.

5. A hand-openable can top comprising a substantially flat plate of a shape similar to that of a can to which

30 it is to be applied, a pair of slits in said plate with the ends of one slit terminating adjacent the respective ends of the other slit, the major portion of each slit being spaced from the corresponding portion of the other slit so as to define a can top portion substantially separate from an encircling portion, and means for effecting displacement of said can top portion relative to the encircling portion so as to provide an opening in said can top for access to the contents of the can, said means including an elongated, relatively stiff, substantially flat

40 strap, said can top portion having means for holding said strap thereto for movement together, said last recited means including an offset formation having end slots through which said strap can extend.

6. A hand-openable can top comprising a substantially

45 flat plate of a shape similar to that of a can to which it is to be applied, a pair of slits in said plate with the ends of one slit terminating adjacent the respective ends of the other slit, the major portion of each slit being spaced from the corresponding portion of the other slit so as to

50 define a can top portion substantially separate from an encircling portion, first means for effecting displacement of said can top portion relative to the encircling portion so as to provide an opening in said can top for access to the contents of the can, and second means for releasably retaining said can top portion in substantially co-planar relationship with the encircling portion.

7. A hand-openable can top according to claim 6 wherein said second means is comprised of a substantially U-shaped clip adapted to embrace upper and lower surfaces of said can top portion and said encircling portion.

60 8. A hand-openable can top comprising a substantially flat plate of a shape similar to that of a can to which it is to be applied, a pair of slits in said plate with both ends of one slit terminating adjacent the respective ends of the other slit providing narrow joinders between adjacent slit ends, the major portion of each slit being spaced from the corresponding portion of the other slit so as to define a substantially central can top portion substantially separate from an encircling portion, frangible sealing means

65 on the underside of said plate for effecting a sealing closure for the top opening of the can when said can top is engaged thereon, and means carried by said can top portion for effecting displacement and rotation of the entire said central can top portion on an axis line passing through said narrow joinders relative to the encircling

portion so as to fracture the frangible sealing means and provide an opening in said can top for access to the contents of the can, said can top portion having a pointed end portion for effecting the fracture.

9. A hand-openable can top comprising a substantially flat plate of a shape similar to that of a can to which it is to be applied, a pair of slits in said plate with the ends of one slit terminating adjacent the respective ends of the other slit, the major portion of each slit being spaced from the corresponding portion of the other slit so as to define a can top portion substantially separate from an encircling portion, frangible sealing means at the underside of said plate for effecting a sealing closure for the top opening of the can when said can top is engaged thereon, an elongated, relatively stiff, substantially flat strap affixed to said can top portion and extending from one end thereof substantially medially of one of the slits for effecting displacement of said can top portion relative to the encircling portion, and said can top portion having a pointed end portion remote from said strap adapted to fracture said frangible sealing means.

10. A hand-openable can top comprising a substantially flat plate of a shape similar to that of a can to which it is to be applied, a pair of slits in said plate with both ends of one slit terminating adjacent the respective ends of the 25

other slit providing narrow joinders between adjacent slit ends, the major portion of each slit being spaced from the corresponding portion of the other slit so as to define a substantially central can top portion substantially separate from an encircling portion, frangible sealing means on the underside of said plate for effecting a sealing closure for the top opening of the can when said can top is engaged thereon, and means carried by said can top portion for effecting displacement and rotation of the entire said 10 central can top portion on an axis line passing through said narrow joinders relative to the encircling portion so as to fracture the frangible sealing means and provide an opening in said can top for access to the contents of the can, said can top portion having a portion for effecting the fracture.
